UNITED STATES PATENT OFFICE.

JOSEPH V. IRENIUS, OF NEWARK, NEW JERSEY, ASSIGNOR, BY MESNE ASSIGNMENTS, TO THE TIN DECORATING COMPANY OF BALTIMORE, OF BALTIMORE, MARYLAND, A CORPORATION OF NEW JERSEY.

TOY.

Application filed February 2, 1922. Serial No. 533,708.

To all whom it may concern:

Be it known that JOSEPH V. IRENIUS, residing at the city of Newark, in the county of Essex and State of New Jersey, has invented certain new and useful Improvements in Toys, of which the following is a full, clear, and exact description.

This invention relates to wheeled toys and has for an object to provide an improved toy of this type which, when motor driven, will travel in a curved path. A further object is to provide an improved wheeled figure toy in which, as it moves over a supporting surface, a toy figure thereon will be given a forward and rearward movement, and in which the vehicle will be concomitantly and repeatedly rocked upon its axle. A further object is to provide an improved wheeled toy in which the movements of a two wheeled cart drawn by a galloping animal and guided by a driver will be realistically simulated. A further object is to provide an improved toy for this purpose which may be produced largely from stock and pressed or stamped sheet material, and which is exceptionally simple, durable and inexpensive. Other objects and advantages will be apparent from the following description and the novel features of the invention will be particularly pointed out in claims.

In the accompanying drawing:

Fig. 1 is a sectional elevation of an embodiment of the invention, showing the parts in two operative positions;

Fig. 2 is a bottom plan of the same; Fig. 3 is a section of the same taken substantially along the line *a—a* of Fig. 1;

Fig. 4 is a transverse section of the same taken substantially along the line *b—b* of Fig. 1; and

Fig. 5 is a fragmentary sectional elevation of the ratchet and pawl taken substantially along the line *c—c* of Fig. 4.

In the illustrated embodiment, a wire 1 is bent in the form of a U with the arms elongated to form the thills 2 of the toy cart or vehicle. A sheet of metal 3 is bent over the base portion of the U-shaped part of the wire to form the body of the vehicle, the edges being secured together and the body to the wire by tongues and apertures as usual in sheet metal toys. A power shaft or axle 4 extends transversely through the sides of the cart or vehicle body and is ro-

tatably mounted therein. Wheels 5 and 6 are mounted upon the ends of the axle, the wheel 6 being fixed upon the shaft or axle for rotation therewith, and the wheel 5 being rotatably mounted thereon. A winding shaft 7 extends through and is rotatably mounted in the side walls of the vehicle body and is provided at one end with a looped portion 8 forming a winding handle. A ratchet wheel 9 is fixed upon the winding shaft 7 abutting against the inner face of one of the side walls of the body, and the body wall has a struck-out tongue 10 acting as a resilient pawl to prevent rotation of the ratchet wheel in one direction, one edge of each tooth of the ratchet wheel having a cam surface for camming the struck-out tongue from its path when rotating in one direction, the tongue snapping behind each tooth as it passes to prevent retrograde movement. A spur gear 11 is rotatably mounted upon the winding shaft 7 at a point adjacent the inner face of the other side wall of the body of the vehicle and carries a sleeve 12 extending around the winding shaft 7 to a point adjacent the ratchet wheel. A helical wire power spring 13 surrounds the sleeve 12 and is anchored at one end to the sleeve 11 and at its other end to the ratchet wheel.

A combined spur gear 14 and pinion 15 is rotatably mounted upon a rod 16 extending between the side walls of the body of the vehicle, and the gear 14 is disposed between the gear 11 and the adjacent wall of the body of the vehicle, the gear 11 meshing with the pinion 15 and holding the combined gear and pinion between it and the adjacent side wall of the body. The gear 14 meshes with a pinion 17 fixed upon the axle or shaft 4 to drive the same. Thus, when the winding shaft 7 is rotated through the handle 8, the ratchet wheel will be rotated and through its connection to one end of the power spring will tension the latter. When the vehicle is free to operate, the gear 11 which is rotatably stressed by its connection to the other end of the power spring will, through the pinion 15, gear 14 and pinion 17 rotate the axle or shaft, and through the fixed wheel 6 thereon will cause a movement of the cart or toy across a supporting surface. Because of the fact that the wheel 5 is loose upon the axle, the vehicle or toy

will move in a curved path very close to that of a circle, which enables the use of the toy in small rooms without danger of the toy colliding with the walls of the room and becoming damaged thereby. The sheet 3 is carried forwardly and bent upon itself to form the floor board 18 and the dash board 19 for the driver. Tongues 20 are struck downwardly from the floor board section of the sheet 3 into parallel positions to form bearings for a roller 21 which limits the forward rocking movement of the vehicle body upon its axle. The portion 22 of the axle 4, which is between the walls of the body, is offset to form a crank device. A pair of links 23 are pivotally connected at one end to the crank device 22 of the axle and pass loosely through slots or apertures 24 in the upper wall of the vehicle body. A figure toy 25 is carried by the upwardly extending ends of the links 23 and in the preferred embodiment, this figure represents a driver for the vehicle, the body of the cart being provided with a U-shaped flange 26 upon the upper wall to represent a driver's seat. As the axle 4 rotates, the figure 25 will be given up-and-down and also repeated forward and rearward movements, the slots 24 serving as relatively sliding fulcrums for the links 23. A toy animal 27 is pivoted at a point intermediate of its length between the forwardly extending ends of the thills so as to be normally supported slightly above the surface over which the vehicle is passing. A pair of flexible cords or reins 28 pass from the nose of the animal to the arms of the driver and form a connection between the same, so that as the toy figure of the driver moves forwardly and rearwardly, an oscillation of the animal upon its pivot will be produced which simulates somewhat the galloping of an animal when drawing a vehicle. The pivotal point of the animal to the thills is located between the center of gravity of the animal and the vehicle when the animal is in its normal upright position, so that when the flexible cords 28 are released as the toy figure of the driver moves forwardly, the action of gravity will cause the animal to rock forwardly. The vehicle, with the toy figures carried thereby, is balanced upon the axle 4 when the toy figure of the driver is in a position intermediate of the limits of its forward and rearward movements, so that as the driver is moved forwardly and rearwardly by the crank device during the propulsion of the vehicle over the supporting surface, the line of direction of the center of gravity of the cart or vehicle with its parts, will be shifted first to one side and then to the other of the axle, so as to cause a rocking of the vehicle or cart upon its axle which also simulates somewhat the movements of a two wheeled cart or vehicle when drawn by a

galloping draft animal. To prevent too rapid operation of the cart, a brake tongue 29 may be struck out from a side wall of the body of the cart to yieldingly press against the face of the gear 11 and frictionally retard its rotation. 70

In use the spring motor 13 of the toy is wound by grasping and rotating the handle loop 8 of the winding shaft, retrograde movement being prevented by the pawl and ratchet device. When the vehicle is placed upon a supporting surface and released the energy of the spring will be transmitted through gears 11, 15, 14 and 17 to the shaft 4 to rotate the same and with it the wheel 6 fixed thereon. The cart or vehicle will then be propelled across the supporting surface. At the same time, the crank device will reciprocate and oscillate the links 23 and impart a corresponding movement to the toy figure of the driver. As the figure of the driver moves rearwardly through the full line position shown in Fig. 1, the pull of gravity will be along its line of direction and will pass to the rear of the axle, and consequently the cart will be tipped rearwardly upon its axle into the position shown in dotted lines in Fig. 1. At the same time the rearward movement of the driver will oscillate the figure of the toy animal in a similar direction very much as a draft animal is pulled up by the guiding reins of the driver, the roller 21 during this movement, leaving the supporting surface. Engagement of the gear 11 of the cart with the supporting surface limits the rearward tilting movement. As the vehicle continues to move across the supporting surface, the figure of the driver will be carried forwardly through the position shown in full lines in Fig. 1, and the pull of gravity will then be shifted forwardly of the axle 4 which causes the vehicle body to be rocked forwardly upon its axle until the roller 21 is again brought into contact with the supporting surface to limit further forward rocking movement. At the same time, the reins 28 will be released and the figure of the animal will rock forwardly upon its pivotal connection to the thills to simulate the movement of a draft animal when galloping. This operation will be repeated as the vehicle is propelled across the supporting surface and provides the very realistic simulation of a two wheeled figure which is drawn by a galloping draft animal and guided by a driver through the usual reins. 100

While the vehicle has been described as having one loose and one fixed wheel upon the axle so as to cause the vehicle to travel in a curved path, it will be understood that if it is desired to have the vehicle travel in a straight line both of the wheels may be fixed upon the shaft or axle. It will be obvious that various other changes in the de- 110

tails and arrangement of parts therein described and illustrated may be made by those skilled in the art within the principle and scope of the invention.

5 I claim:

1. A toy comprising a wheeled metal body, pivoted upon an axle, propelling means therefor, a connection from such propelling means to the body whereby the body is oscillated about the axle as a centre, an animal figure connected to the body by shafts the ends of which form an axis about which the animal figure oscillates, and a connection between the animal figure and the body eccentric to the axis of oscillation of the figure, the oscillation of the body thus causing the animal figure to oscillate about its axis, and also to be lifted from its horizontal plane.
- 10 2. A toy vehicle comprising a body, a wheeled axle upon which the body is balanced, a driver figure, a link connecting the driver and axle, the axle having a crank co-operating with the link so that oscillation of the link agitates the driver figure and causes oscillation of the vehicle-body, an animal figure, shafts connecting the body and the animal figure, the ends thereof forming an
- 15 axis about which the animal may oscillate, and a connection between the driver and the animal eccentric to the axis of oscillation of the figure, the arrangement being such that as the vehicle progresses the body is oscillated, the driver is agitated, and the animal is both oscillated and lifted, so that it appears to gallop.
- 20 3. A toy vehicle comprising a body carried by, and balanced on, a cranked axle, a driver, a link from the crank to the driver, means for limiting the movement of the body on either side of its balanced position, in combination with an animal, shafts connecting the animal and the body, the ends of the shafts forming a bearing upon which the animal oscillates, and a connection between the driver and the animal eccentric to the axis of oscillation of the latter, the arrangement being such that the movements of the driver destroy the balance of the body and cause it to oscillate, and the animal to oscillate and bodily to rise and fall to simulate galloping.
